ABSTRACT

A pallet rack in which the upright members have slots to receive tongues of a shelf beam connector, and the shelf beam connector embraces the upright by its sidewall and by integral offset fingers; the tongues are held against disengagement by pivotable latches which are engageable and disengageable from the tongues.

BACKGROUND OF THE INVENTION

Field of Invention

This invention relates generally to pallet racks, and particularly to pallet racks in which shelf beams are easily adjustable, and the load does not tend to deform the rack.

Prior Art

Pallet racks are in wide use in industry for receiving and holding pallets upon which bulky and heavy materials are held in storage. The shelf beams are frequently bolted in place and must be unbolted in order to change position. Height adjustments are cumbersome, time consuming, and require the application of tools in order to lock the shelves in place, or to unlock them in order to adjust them. Many shelf beam connectors for racks have downwardly extending, deflected fingers, so that downward movement is required to put them in place, and they must be lifted up to remove them. In some racks, the shelf beam connectors are permanently riveted in place so that adjustment cannot be made. What is perhaps the greatest difficulty arises from shelf beam connectors that exert torque on the uprights, tending to twist and deform them, so that the rack may lean, or twist and even become top heavy and collapse.

SUMMARY OF INVENTION

It has been found that a novel rack, utilizing a novel shelf beam connector, can be provided which overcomes many of the disadvantages of known racks. Such a novel rack may include a connector member for engagement with a vertical member, a front wall on the connector member, an integral sidewall on the vertical edge of the front wall, an integral slotted tongue on the front wall in general parallelism with the sidewall, an integral offset finger on the front wall, deflected toward the sidewall and a latch member engaged with the tongue.

A shelf beam connector according to the invention may include a connector member having a front wall, an integral sidewall on a vertical edge of the front wall and an integral tongue on the front wall in general parallelism to the sidewall, deflected toward the sidewall. Such a shelf beam connector is invertible so that each shelf can be set at each of two different heights. The shelf beam connector may be connected and disconnected merely by horizontal movements to engagement and disengagement with an upright. The shelf beam connector exerts little torque on an upright, but rather exerts a sheer stress, so that the rack does not twist or lean. A novel auxiliary latch is pivotably engaged and disengaged from a tongue on the connector, with the result that, the shelf beam connector is easily secured in place against disengagement, and may be easily unlatched for adjustment. Offset fingers engage the flange of the upright and prevent pivoting in the opposite direction, so a completely stable rack is provided.

DRAWINGS

Referring now to the drawings in detail:

FIG. 1 is a perspective view of a shelf beam rack, with one of the beams inverted;

FIG. 2 is a left side perspective view of a shelf beam connector;

FIG. 3 is a right side perspective view of the shelf beam connector;

FIG. 4 is a front elevational view of a U-upright;

FIG. 5 is a front elevational view of an I-upright;

FIG. 6 is a side elevational view of a latch;

FIG. 7 is an end elevational view of the latch;

FIG. 8 is an opposite side elevational view of the latch;

FIG. 9 is a top plan view of the shelf beam connector engaged with an I-upright;

FIGS. 10 and 11 are perspective views showing the latch and a tongue, with an arrow indicating the direction of movement of the latch to engage with the tongue for pivotable latching;

FIG. 12 is a side elevational view showing the latch moved to latching position;

FIG. 13 is a perspective view of the latch engaged with the tongue, the arrow showing the direction of pivotal movement of the latch, for latching;

FIG. 14 is a top plan view of a J-hook used to lock the connector and upright together; and

FIG. 15 is a perspective view showing the latch seated in latching position on the tongue.

10

PREFERRED EMBODIMENTS

Referring now to the drawings in detail, the rack utilizes an upright or vertical column 11 which may take several different forms, such as an I-beam 12 or a U-beam 13. A foot or pedestal 14 is welded to the bottom of the column 11 to provide stability. The column is provided with slots 15 in the web 16. A slot 15 is positioned adjacent to each flange 17 on the web 16, for cooperative engagement with a connector.

15 The connector 10 has a front wall 18. There is a first sidewall 19 extending perpendicular and rearwardly on one vertical edge of the front wall. On the opposite vertical edge of the front wall 18, there is a short, perpendicular second sidewall 20, from which pairs of tongues 21 extend in the same

25 vertical plane as the second sidewall 20. These tongues 21, are cooperative with pairs of slots in the web 16, and enter them and extend beyond the web. The front wall 18 is provided with two groups of three intersecting cuts 22, which define fingers 23. The fingers 23 are deflected inwardly from the front wall 18 to engage the flange 17, and this way provide stability, and prevent wavering and rocking. A shelf beam 24 is welded to the connector 10. The shelf beam 24 may be attached at the top of the sidewall 19, of the connector 10 by being welded thereto. The connector 10 may then be reversed, providing a high or a low position for the shelf beam 24, on either of which, objects may be stored. It is to be noted that in either of these two positions of the shelf beam assembly, the supporting strength of the shelf is equal. It is also to be noted that any vertical force exerted on the shelf beam does not unseat it. With the holes in the upright 11 on 4 inch centers, the reversal of the shelf permits adjustment on 2-inch centers.

30 For retaining the shelf beam connector 19 in engagement with the upright 11, the tongues 21 must be held against disengagement from web 16. This is accomplished by pivotal latch 25, that may be easily engaged or disengaged from the tongues 21. Each tongue 21 has a slot 26 at its outer end. The latch 25 is mounted pivotably in the slot 26 by being positioned on its side as shown in FIG. 10. The first side 27, on the main wall 28 has a cut which defines an inturned lug 29. This lug 29 is moved into slot 26 as indicated by the arrow between FIGS. 10 and 11, and the latch 25 assumes the position shown in FIG. 13. The latch 25 is pivoted downwardly (note arrow in FIG. 12) so that its first side 9 embraces the tongue 21, and the main wall 28 rests on the top of the tongue 21. The arcuate edges 30 will slide by the web and the latch will be in abutment by its flat ends 31, with the web 16, preventing the tongue 21 from disengaging from the slots 15 in the web. By pivoting the latch 25, and withdrawing the lug 29 from the slot 26, the tongue can be withdrawn from the upright 11 to reposition the shelf beam 24 with the greatest of ease.

8840 8845 8850 8855 8

- b. a web on the vertical member,
  - c. a flange on the web,
  - d. a connector member engageable with the vertical member,
  - e. a front wall on the connector member in abutment with a vertical edge of the flange,
  - f. an integral sidewall on a vertical edge of the front wall,
  - g. an integral slotted tongue on the front wall in general parallelism with the sidewall,
  - h. an integral offset finger on the front wall, deflected toward the sidewall,
  - i. the sidewall positioned in abutment with the side of the flange on the web,
  - j. the offset finger in abutment with the opposite side of the flange on the web,
  - k. the tongue passed through a hole in the web;
  - l. a pivotable latch member engageable and disengageable with the tongue,
  - m. a main wall on the latch member,
  - n. an integral first sidewall on the main wall,
  - o. a portion of the first sidewall bent into general parallelism with the main wall,
  - p. an integral second sidewall on the main wall opposite and generally parallel with the first sidewall,
  - q. a portion of the second sidewall opposite to the bent portion, cut away to allow the bent portion to be inserted into the slot of the tongue.
2. A rack comprising
- a. a vertical member,
  - b. a web on the vertical member,
  - c. a flange on the web,
  - d. a connector member engageable with the vertical member,
  - e. a front wall on the connector member in abutment with a vertical edge of the flange,
  - f. an integral sidewall on a vertical edge of the front wall,
  - g. an integral slotted tongue on the front wall in general parallelism with the sidewall,
  - h. an integral offset finger on the front wall deflected toward the sidewall,
  - i. the sidewall positioned in abutment with the side of the flange on the web,
  - j. the end of the offset finger in abutment with the opposite side of the flange on the web,
  - k. the tongue passed through a hole in the web.
3. A rack according to claim 2 and further including
- a. a vertical member engaged with the connector member,
  - b. a J-bolt with the vertical member at one end and the opposite end passed through the shelf beam secured thereto.
4. A rack comprising
- a. a connector member for engagement with a vertical member,
  - b. a front wall on the connector member,
  - c. an integral sidewall on a vertical edge of the front wall,
  - d. an integral slotted tongue on the front wall in general parallelism with the sidewall,
  - e. an integral offset finger on the front wall, deflected toward the sidewall,
  - f. a latch member engaged with the tongue.
5. A rack comprising
- a. a connector member for engagement with a vertical member,
  - b. a front wall on the connector member,
  - c. an integral sidewall on a vertical edge of the front wall,
  - d. an integral slotted tongue on the front wall in general parallelism with the sidewall,
  - e. an integral offset finger on the front wall, deflected toward the sidewall,
  - f. a latch member engaged with the tongue,
  - g. a main wall on the latch member,

- 4
- h. an integral first sidewall on the main wall,
  - i. a portion of the first sidewall bent into general parallelism with the main wall,
  - j. an integral second sidewall on the main wall opposite and generally parallel with the first sidewall,
  - k. a portion of the second sidewall opposite to the bent portion, cut away to allow the bent portion to be inserted into the slot of the tongue.
6. A shelf beam connector comprising
- a. a connector member having a front wall
  - b. an integral sidewall on a vertical edge of the front wall,
  - c. an integral tongue on the front wall in general parallelism with the sidewall,
  - d. an integral offset finger on the front wall, deflected toward the sidewall.
7. The shelf beam connector according to claim 6 and a shelf beam connected thereto.
8. The shelf beam connector according to claim 6 and a slot in the tongue.
9. The shelf beam connector according to claim 7 and a slot in the tongue.
10. The shelf beam connector according to claim 8 and a pivotable latch engaged with the slot.
11. A shelf beam connector latch comprising
- a. a latch member having a main wall,
  - b. an integral first sidewall on the main wall,
  - c. a portion of the first sidewall bent into general parallelism with the main wall,
  - d. an integral, second sidewall on the main wall opposite and generally parallel with the first sidewall,
  - e. a portion of the second sidewall opposite to the bent portion cut away to allow the bent portion to be inserted in a slot.
12. A shelf beam connector latch comprising
- a. a connector member having a front wall,
  - b. an integral sidewall on a vertical edge of the front wall,
  - c. an integral torque tongue on the front wall in general parallelism with the sidewall,
  - d. an integral offset finger on the front wall, deflected toward the sidewall,
  - e. a slot in the tongue,
  - f. a latch member having a main wall,
  - g. an integral first sidewall on the main wall,
  - h. a portion of the first sidewall bent into general parallelism with the main wall,
  - i. an integral second sidewall opposite and generally parallel with the first sidewall,
  - j. a portion of the second sidewall, opposite to the bent portion, cut away to allow the bent portion to be inserted in the slot in the tongue,
  - k. the bent portion of the first sidewall inserted into the slot in the tongue,
  - l. the latch member pivotable on the bent portion in the slot, to position its main wall, first and second sidewalls astride the tongue to block the withdrawal of the tongue from the hole in a web.
13. A rack comprising:
- a. a connector member,
  - b. a front wall on the connector member,
  - c. an integral sidewall on a vertical edge of the front wall,
  - d. at least one tongue on the front wall in general parallelism with the sidewall,
  - e. an integral offset finger on the front wall, deflected toward the sidewall,
  - f. the end of the integral, offset, deflected finger and the sidewall defining between them a space to receive a flange of a vertical member,
  - g. the tongue on the connector positioned to be passed through the web of a vertical member.
